(57) **CLAIM**

I claim the ornamental design for a guidewire loader apparatus for a medical device, as shown and described.

DESCRIPTION

FIG. 1 is a reduced top perspective view of a guidewire loader apparatus for a medical device showing my new design;

FIG. 2 is an exploded top perspective view thereof, showing a lower first component and an upper second component thereof;

FIG. 3 is an enlarged front elevation view of the perspective view of FIG. 1;

FIG. 4 is a top plan view of the lower component from the perspective view of FIG. 2, shown with the upper component removed for ease of illustration.

FIG. 5 is a bottom plan view thereof;

FIG. 6 is a front elevation view thereof;

FIG. 7 is a rear elevation view thereof;

FIG. 8 is a right side elevation view thereof;

FIG. 9 is a left side elevation view thereof;

FIG. 10 is a bottom plan view of the upper component from the perspective view of FIG. 2, shown with the lower component removed for ease of illustration.

FIG. 11 is a top plan view thereof;

FIG. 12 is a front elevation view thereof;

FIG. 13 is a rear elevation view thereof;

FIG. 14 is a right side elevation view thereof; and,

FIG. 15 is a left side elevation view thereof.
